CLAIM

The ornamental design for jewelry with brackets and charms, as shown and described.

DESCRIPTION

FIG. 1 is a perspective view of jewelry with brackets and charms showing our new design;

FIG. 2 is a front elevational view thereof;

FIG. 3 is a top plan view thereof;

FIG. 4 is a side elevational view thereof taken from a different angle of view from than FIG. 2;

FIG. 5 is a side elevational view thereof taken from a different angle of view than FIGS. 2 and 4;

FIG. 6 is a side elevational view thereof taken from a different angle of view than FIGS. 2, 4 and 5;

FIG. 7 is a bottom plan view thereof;

FIG. 8 is a perspective view thereof, shown in use; and,

FIG. 9 is a perspective view thereof, shown with the back of the owl-shaped charm separated.

With regard to FIG. 8, the broken lines in the drawing represent environmental matter that forms no part of the claimed design.
